UNITED STATES PATENT OFFICE.

AMBROSIUS BRIECHLE, OF BROOKLYN, NEW YORK, ASSIGNOR TO WALES ADDING MACHINE COMPANY, OF WILKES-BARRE, PENNSYLVANIA, A CORPORATION OF PENNSYLVANIA.

ACCOUNTING-MACHINE.

1,336,192.

Specification of Letters Patent.

Patented Apr. 6, 1920.

Application filed December 6, 1916. Serial No. 135,352.

To all whom it may concern:

Be it known that I, AMBROSIUS BRIECHLE, a citizen of the United States, residing in the borough of Brooklyn, city and State of New York, have invented new and useful Improvements in Accounting-Machines, of which the following is a specification.

Modern calculating machines include selective mechanism, as a keyboard, on which amounts are set up to be accumulated on a series of counters. Printing devices co-operate with a platen mounted on a carriage removably secured to the frame of the machine, to list the amounts set up on the keyboard, on a paper web or work sheet on the platen.

Heretofore, means have been provided to successively feed separate work pieces, as envelops, for instance, to the printing devices, and to discharge them from in front of such devices.

One object of the present invention is the provision of a simplified and novel means to feed separate work pieces singly and successively to the printing devices, and to eject the work pieces from in front of the printing devices, such means being driven from the calculating machine as an incident to the operation of such machine in registering amounts on the accumulators. The mechanism of the invention is positive in its operation, and comprises but few parts not liable to get out of order.

Another object is to positively effect the printing of the amounts, or the location of the writing line, on the respective work pieces, at a predetermined point.

A further object is to effect the advance of the work pieces to the printing devices and their discharge from in front thereof by a single self-contained injector and ejector mechanism.

A still further object is to positively insure the feed of the envelops singly to the printing devices, which I accomplish by the provision of a novel feed mechanism adapted to engage beneath the flaps of the individual envelops to withdraw them one by one from the storage compartment.

50 The flap of the foremost envelop lifts sufficiently to admit of the insertion of the feed device between the flap and the body of the envelop when the envelop is to be advanced.

In addition, I provide restraining means, the operation of which is synchronized with the operation of the feeding means, to prevent the withdrawal of additional envelops by reason of frictional contact with the positively fed envelop.

Still another object is to enable the operator to list the several amounts on an independent paper, in addition to printing such amounts on the separate work pieces, from a single set of printing devices, and to this end I have contrived a combined envelop and paper feeding device, whereby the envelops and paper web lie one behind the other relatively to the printing devices, with a transfer medium, as carbon, interposed between the paper and the envelops. The side of the paper web facing the envelops may be coated with carbon to effect the imprint of the amounts on the envelops, or a separate carbon web may be used.

Another object is the provision of compact and simple means driven from the calculating machine incidentally to the accumulation of items therein, to operate the paper feeding means and the injector and ejector mechanism, as well as the restraining means which prevents the frictional withdrawal of the envelops from the storage compartment.

A further object is the provision of a self-contained device of this nature which is readily attachable to a calculating machine equipped with printing devices, in place of the carriage with which such machines are provided, and detachable therefrom, to enable the carriage to be replaced. The operator can thus list amounts on envelops or other separate work pieces automatically fed to the printing devices, on the same machine which he uses for ordinary work, by the mere substitution of the envelop feed mechanism for the carriage, and vice versa.

To these and other ends, my invention includes certain novel features and combinations of parts, all of which will be more fully set forth hereinafter and particularly referred to in the claims.

In the accompanying drawings:

Figure 1 is a left side view of the invention applied to the well known Wales calculating machine, the parts being in normal idle position;

Fig. 2 is a right hand sectional view of the invention detached from the machine, the parts being in their normal positions, as when attached, showing an envelop with 5 drawn from the storage compartment, and the previously fed envelop being ejected;

Fig. 3 is a front view, parts being broken away to disclose those behind;

Fig. 4 is a right hand sectional view, 10 showing the positions assumed by the parts at the end of the forward stroke, preparatory to withdrawing an envelop and ejecting the previously fed envelop;

Fig. 5 is a transverse sectional view on 15 line $x-x$ of Fig. 4, looking in the direction of the arrow;

Fig. 6 is a detail perspective view, showing the injector and ejector mechanisms, and the restraining means to prevent the frictional withdrawal of the envelops from the 20 storage compartment;

Fig. 7 is a fragmentary detail perspective view of a part of the outer or confining wall of the passageway or channel 25 through which the envelops are advanced to the printing devices;

Fig. 8 is a right hand side view of the 30 invention, showing the means which operates the restraining means to prevent the frictional withdrawal of the envelops;

Figs. 9 and 10 are detail sectional views, taken at right angles to each other, showing the motor spring which drives the operating parts to their effective positions upon the withdrawal of the usual Wales thrust 35 bar, and

Fig. 11 is a detail rear view of the envelop guide fingers on the arresting plate, and the follower plate.

I have chosen to illustrate this invention 40 in connection with the familiar Wales calculating machine, it being understood that my device is not limited in its application thereto, but may be attached to other machines as well.

Referring to Fig. 1, the base 965 of the adding machine supports side frames 967 between which are mounted the keyboard, the accumulating, and the printing sections 50 in sequence from front to rear.

The keys 117 are arranged in denominational orders to correspond with the individual counters 490 and drive members 310 of the accumulating mechanism, and the individual typecarriers 514 of the printing section.

Amounts are accumulated on the counters as follows:

Depressing keys 117 rocks levers 116 to 60 project stops 115 into the paths of the corresponding drive members or racks 310, thereby displacing the rack detents 221 normally in the paths of the racks.

A series of front arms 312 and rear arms 65 311 pivotally support the respective racks

310, the front arms being journaled on a cross shaft 300 extending between the side frames 967, and the rear arms 311 being journaled on a cross rod 301. A restraining and restoring bar 205 connected to a crank 70 220, normally lies across the paths of the front rack-supporting arms 312 to prevent the racks from advancing under the influence of their drive springs 383, preferably connected to the rear supporting arms 311 75 and the bar 205.

Turning a main drive shaft 200 forwardly, by means of a handle 210^a, for instance, rocks an arm 210 fast on the shaft, its free end traversing a cam slot 220^a in 80 the crank 220, to swing the crank and withdraw the restraining and restoring bar from in front of the arms 312.

The springs 383 then advance the racks until the latter are arrested by contact with 85 the projected stops 115, or the rack detents 221 in those denominations wherein no keys have been depressed.

A series of individually rotatable counters 490 with their respective pinions 435 90 are independently journaled on an axle 400 normally supported by means, not shown, with the pinions disengaged from the racks.

The main drive shaft, on its forward stroke, advances links 214, one of which is 95 shown connected at one end to the arm 210, and at its other end to a counter-controlling trip rod 303 suspended by hangers 323 from the cross shaft 300. As the main drive shaft and the trip rod approach the ends 100 of their forward strokes, (at which time the racks 310 have reached their advanced positions) the counter-supporting mechanism, not shown, is tripped by the rod 303 to enable the pinions 435 of the respective counters, to mesh with the advanced racks.

The main drive shaft on its return stroke, 105 rocks the crank 220 through the arm 210, to cause the restraining and restoring bar 205 to return the advanced racks, which 110 racks, during their retirement, turn the counters 490 to register thereon the amount set up on the keyboard.

The main drive shaft on its return stroke, also retires the trip rod 303 which, near the 115 end of the return stroke, operates the counter-supporting mechanism to disengage the pinions 435 from the racks 310 subsequently to the retirement of the latter.

Suitable carrying mechanism (not shown) 120 transfers the tens from right to left in the usual manner.

The printing of amounts set up on the keyboard is accomplished, as follows:

The rear rack-supporting arms 311 carry 125 rearward extensions 311^a connected by links 515 to the stems of type-carriers 514 in which the types 561 are mounted. The arms 311 as they rock on the forward stroke to advance the racks 310, raise the extensions 130

311^a and the typecarriers 514 to position the proper types at the printing line.

Latches 511 journaled on a cross rod 504, normally lock the spring-driven printing 5 hammers 510 journaled on a cross shaft 500, in cocked positions, the latches being provided with the usual cross over tails 511^a to effect cipher printing to the right.

As the extensions 311^a rise to position the 10 types, they free suitably supported trip bars 513 to the action of lifting springs 583, to enable the upper ends of the bars to contact and disable the latches 511, in those 15 denominations wherein keys have been depressed.

A universal catch 518 mounted on a shaft 536 restrains the hammers against firing upon the release of the individual latches.

The trip rod 303 tensions the hammer 20 drive springs 580, withdraws the hammer-resetting bail 509, and releases the universal catch 518 through the following train of mechanism. On its forward stroke, the trip rod advances a link 526 connected to one 25 arm of a lever 524 pivoted at 508, to rock the lever. A link 527 connected to the opposite arm of the lever 524 transmits motion therefrom to a lever 525 fast on the cross shaft 500. A link 525^a connects this lever with an 30 arm 513^a on a shaft 502^a which supports a tensioning bail 505^a (shown in dotted lines in Fig. 1) to raise the bail and tension the hammer-driving springs 580 extending between the bail and the respective hammers 35 510.

Arms 519 on the shaft 500 carry the hammer-resetting bail 509 normally in contact with the hammers.

The lever 525 as it turns, rocks the reset- 40 ting bail out of the paths of the hammers.

A releasing link 526 connected to the lever 45 525, has a slot and pin connection 555^a with an arm 517 on the universal catch-supporting shaft 536, and near the end of the forward stroke, after the types have been positioned, the link 526 swings the arm 517 to displace the universal catch and permit the hammers 510 to drive the types against the paper. A ribbon 890 is interposed between the types and the paper to enable the 50 printing of the amount.

The racks 310 on their retirement, return the rear extensions 311^a to retract the typecarriers 514 to normal position and lower 55 trip bars 513 against the tensions of the springs 583, thereby freeing the individual latches 511. Springs (not shown) restore the latches to effective position. The trip rod 303 on its return through the linkage 60 526, 524, 527, and 525, forces the hammer-restoring bail 509 against the discharged hammers to cock the latter, relaxes the tension of the hammer-driving springs 580, and frees the universal catch 518 for effective 65 operation.

The machine may be provided with a paper carriage (not shown) including a paper supply, a platen, and line spacing mechanism, which carriage is removably secured to the rear ends of the side frames 70 967.

A rearwardly extending thrust bar 2026 (Fig. 1) connected at its forward end to a cross bar 302 mounted in the swinging hangers 323, operates the paper feed mecha- 75 nism on the carriage.

For a further understanding of the Wales machine, attention is directed to U. S. patents to Wales 768,097, August 23, 1904; 794,205, July 11, 1905; and 797,032, August 15, 1905; McFarland and Wales, 880,157, February 25, 1908; and Wales, 940,758, November 23, 1909.

The foregoing mechanism is old and constitutes a part of the present invention only 85 in so far as it is combined with the novel features hereinafter set forth.

A machine of the foregoing type is adapted to accumulate on the counters and record on the paper web or sheet, amounts 90 set up on the keyboard.

Separate work pieces, as cards, envelops, or the like, may be manually inserted around the carriage platen, printed upon, and removed by hand, but this method is slow 95 and laborious, and I have contrived a novel and simple means interchangeable with the usual paper carriage, which automatically presents the envelops to the printing devices, to receive the imprint, after which the envelops are automatically ejected, all of which 100 is effected through the operation of the machine in registering amounts on the counters.

I am aware that in the main, this idea broadly is old, but I am not aware that any- 105 one heretofore has provided an envelop feeding device which may be detachably connected to the usual calculating machine in place of the ordinary paper carriage, thereby extending the field of usefulness of 110 the calculating machine with a minimum of expense.

Heretofore, the location of the writing line on the envelops fed to the printing devices was not definitely positioned, there 115 being no means to aline the envelops and locate the writing line at a predetermined point on each envelop.

In my invention I have provided means whereby the writing line is located at a pre- 120 determined and constant place on each envelop.

In former envelop feeding devices, so far as I am aware, no provision has been made which enables the operator to make and preserve a printed list and a total of the amounts recorded on the several envelops, at the same time that the envelops are being printed upon, and from the same set of devices which print upon the envelops. 125 130

I have contrived a combined envelop and paper feeding mechanism, whereby the amounts are simultaneously printed by a single set of printing devices on the envelops, and upon a separate paper web, the web being advanced step by step past the printing line as the envelops are successively advanced.

Furthermore, it will also be observed that 10 machines wherein it is only desired to accumulate items arranged in a single column, can be equipped with my improvement, and thus avoid the necessity for a so-called "narrow" carriage to print lists on strip paper 15 only.

The operator, with my invention, can list items on the paper web alone, by omitting to supply the device with envelops, and obtain the same result as with an independent 20 fixed carriage equipped to feed strip paper, thereby saving the cost of such independent carriage.

Owing to the varying thicknesses of the envelop stock, there has been a liability of 25 feeding two or more envelops at a time to the printing devices. This resulted because the ledge or shoulder on the slide employed in many machines to engage beneath the bottom edge of the foremost envelop, to advance the envelop, extended under the edge 30 of the next adjacent envelop as well.

I employ a novel envelop withdrawing or feeding means which can only engage the foremost envelop, and associate therewith 35 means to prevent the withdrawal of the next adjacent envelop due to frictional contact with the envelop being withdrawn.

The paper feeding, and envelop advancing and ejecting means, and the means to prevent 40 the frictional withdrawal of additional envelops, are preferably driven from a single compact mechanism actuated from the thrust bar 2026 of the calculating machine, incidentally to the operation of registering and printing amounts.

The particular embodiment of my invention herein illustrated, comprises a supporting fixture 1 (Fig. 1) detachably secured to the side frames 967 by set screws 2 in the 50 same manner as, and in place of, the usual paper carriage. By loosening the screws, the entire self-contained envelop and paper feeding mechanism can be removed and the paper carriage fastened in its place.

55 Side plates 3 (Figs. 1 and 2) extending rearwardly from the fixture 1 to which they are secured, are connected by brace rods 4, and form a casing for the operative parts of the device. An angular container 5 (Figs. 2 and 4) located between the side plates 3 and below the plane of the printing devices, cooperates with the side plates to form a storage compartment for the supply or pack of envelops 6 introduced therewith 60 through the open rear end of the casing.

A follower 7 in the storage compartment operates to press the envelops upwardly against an arresting plate 8 partially closing the upper end of the storage compartment.

Ears 9 on the follower plate 7 pivotally engage a supporting rod 10 traversing arcuate slots 11 in the sides 3, the supporting rod being mounted on the rearwardly extending arms of a pair of external levers 12. These 75 levers are fast on a shaft 13 journaled in and extending between the sides 3 of the casing in front of the angular container 5. Springs 14 connected to the remaining arms of the levers press the plate or follower 7 80 upwardly against the bottom of the pack of envelops.

A spring 15 on the supporting rod 10 contacts the follower plate 7 to cause the automatic adjustment of the latter to the plane 85 of the bottom of the pack of envelops.

Pressing downwardly upon a finger piece 16 extending rearwardly from the follower plate 7, forces the latter down to enable the insertion of a pack of envelops 6 into the 90 storage compartment. Upon its release, the follower 7 and its supporting levers 12, assume a position substantially like that shown by the dot and dash lines in Fig. 2, the springs 14 pressing the follower upwardly.

The envelops in the pack are arranged with their flaps 17 (Fig. 4) uppermost and at the front end of the pack.

Alining guides 18 (Figs. 2, 4 and 11) depend from the rear end of the arresting plate 8 to contact the rear edges of the envelops and maintain them in proper position against sliding rearwardly, the lower free ends of the guides being outwardly curved 105 so that if any of the envelops in the pack project rearwardly beyond the others, they will be gradually slid forwardly by contact with such curved ends as they are pressed upwardly by the follower 7.

The guides 18 are spaced apart as shown in Fig. 11, to accommodate the finger piece 16 of the follower 7, and thereby enable the latter to pass between the guides and press the bottommost envelop against the arresting plate 8, in position to be fed to the printing devices.

The forward end of the arresting plate 8 terminates short of the flaps 17 of the envelops, and is downwardly inclined so that 120 the envelops are slightly squeezed between the follower and the front edge of the arresting plate at a point just clear of the free ends of the flaps, to loosen the flap of the uppermost envelop, and cause it to lift or 125 spring upwardly above the body portion of the envelop.

The envelops are conveyed from the storage compartment through a channel or passage formed between an outer semi-circular 130

confining plate 19 (Figs. 2, 3, 6 and 7) embraced between the upper forward ends of the main side plates 3, and upper and lower guide plates 20 and 21 concentric with the 5 confining plate. The guide plates 20 and 21 are supported at their lateral edges by stationary end frames 22 parallel with and inclosed between the side plates 3. A brace rod 4 and a rock shaft 23 extending between 10 the side plates 3 support the end frames 22. The adjacent edges of the guide plates 20 and 21 are spaced apart from each other, the lower guide plate having a rearward extension 24 (Figs. 2 and 4) projecting over 15 the upper end of the storage chamber and being inclined above the plane of the stop plate 8 to enable the flap 17 of the envelop to swing upwardly above the body portion, as shown.

20 The upper edge of the upper guide plate 20 joins the upper edge of an angular partition 25 (Figs. 2 and 4) having a sloping bottom to facilitate the removal of the envelops, which partition is fixed between the 25 side plates 3 above the storage compartment, to form a receiving or collection compartment for the envelops as they are printed.

The lower edge of the outer confining plate 19 joins the upper edge of the angular 30 container 5 (Fig. 7), and merges at its upper edge into a top plate 26 extending between the side plates 3 to form the cover for the receiving or collection compartment.

A swinging gate 27 having ears 28 pivoted 35 to the side plates 3 at 29, may close the open rear end of the receiving compartment, to retain the printed envelops as they are discharged from in front of the printing devices.

40 It will be noted that the passage through which the envelops travel extends from the upper end of the storage, to the upper end of the receiving compartment.

The periphery of a platen 30 mounted on 45 pintles 31 journaled in the end frames 22 opposite the printing devices, extends into the passageway between the adjacent edges of the upper and lower guide plates 20 and 21, the outer wall of the passageway or 50 channel formed by the confining plate 19 lying tangentially to the periphery of the platen and being cut away, as shown in Fig. 3, at a point opposite the printing devices to permit the latter to strike against the 55 platen at the printing line.

The means for positively withdrawing the envelops singly and successively from the storage compartment and advancing them past the printing devices, comprises a pair 60 of injector arms or carriers 32 fixed to the rock shaft 23 and lying parallel with and adjacent the respective outer faces of the supporting plates 22. In the particular form herein selected for illustration, the injector arms terminate in substantially tri-

angular ends, from the rear corners of which project curved injecting fingers or members 33, the forward ends of which traverse the passage between the storage and receiving compartments, along the sides of the upper 70 and lower guide plates 20 and 21 which are narrower than the outside confining plate 19 (see Fig. 3).

A coil spring 34 (Figs. 5, 9 and 10) encircles one end of the drive shaft 23 which 75 is journaled in and projects beyond the side plates 3. One end of the spring is secured to an inclosing housing 35 fastened to the side plate 3, the opposite end of the spring being secured to the drive shaft 23 to turn 80 the latter in one direction. A shrouded gear 36 on the opposite projecting end of the rock shaft 23 meshes with a toothed segment 37 fixed to an intermediate shaft 38 conveniently journaled in the opposite side 85 plates 3 and carrying a crank 39 having a crank pin 40 normally contacted by the rearwardly projected thrust bar 2026, which, through the drive segment 37, normally holds the carrier arms 32 and injector fingers 90 33, in their advanced positions (Fig. 2), against the tension of the motor spring 34. An anti-friction roll 41 (Fig. 3) may be mounted on the crank pin 40.

On the forward stroke of the main drive 95 shaft 200, the thrust bar is withdrawn relatively to the crank pin 40 to free the rock shaft 23 to the action of the motor spring 34 which thereupon turns the shaft 23 on its forward stroke to swing the injector fingers 100 100 or members 33 downwardly and rearwardly from their normal advanced positions, shown in Fig. 2, to their retracted or potentially effective positions, shown in Fig. 4, during which movement, the fingers 33 traverse the channel or passageway between the outer confining plate 19 and the guide plates 20 and 21, and enter the upper forward end of the storage chamber, where they come to rest along the opposite edges of the rearward 110 extension 24 of plate 21, with their free ends projecting below the extension 24 in position to enter between the raised flap 17 and the body of the uppermost envelop. The fingers, as they pass from the channel into the 115 storage compartment, ride over and past the flap 17 of the uppermost envelop of the pack 6, to slightly compress the envelops, and then swing away from the pack to suddenly release the pressure and thereby loosen the 120 flap of the foremost envelop, if it should happen to adhere to the body of the envelop, to enable the flap to spring upwardly.

The gear 36 on the shaft 23 rotates the segment 37 to cause the crank pin 40 to follow 125 the thrust bar as the latter is withdrawn.

The main drive shaft 200 on its return, presses the thrust bar 2026 against the crank pin 40, turning the crank to swing the toothed segment 37 in the opposite direction 130

and rotate the shaft 23 on its return stroke, thereby restoring the injector fingers to normal position (Fig. 2).

The rock shaft 23 on its return stroke, advances the injector fingers 33 to insert them beneath the lifted flap 17 of the uppermost envelop, the front ends of the fingers engaging in the crease at the juncture of the flap with the body of the envelop to positively withdraw the envelop from the storage compartment and advance it along the passageway past the printing devices. The extension plate 24 prevents the flap from swinging too far upward, which might permit the injector fingers to mutilate the envelop.

To prevent the advancing envelop from drawing with it by frictional contact, one or more of the adjacent envelops, I provide a restraining mechanism (Figs. 2, 3, 4, and 8) which, in the present instance, comprises a supporting bar 42 extending between and projecting through slots 43 in the side plates 3 at the upper end of the angular storage container 5. Arms 44 fixed on a cross shaft 45 journaled in the side plates 3, carry the supporting bar, on which latter are mounted restraining lugs or members 46 operating in slots 47 (Fig. 7) cut in the upper end of the angular container 5 at its juncture with the confining plate 19, and extending across the mouth of the passage leading from the storage compartment. A spring 48 (Fig. 8) presses a wiper 49 on the shaft 45, against a cam 50 fixed on the rock shaft 23, which cam normally maintains the restraining lugs 46 in effective position across the passage leading from the storage compartment to prevent the withdrawal of the envelops or work pieces, as shown in Figs. 2 and 8. The mechanisms are so timed that, as the injector members 33 are swung downwardly and rearwardly from their normal positions (Figs. 2 and 6) to their potentially effective positions (Fig. 4), the cam at first maintains the restraining lugs 46 in effective position, but as the injector members approach the lugs, the high point of the cam 50 retires from the wiper 49, as shown in dotted lines in Fig. 8, to enable the spring 48 to swing the arms 44 and shift the restraining lugs 46 to inactive position out of the path of the injector members and out of the channel, as shown in Fig. 4.

The restraining lugs 46 remain in idle position during the first part of the return stroke of the rock shaft 23 which restores the injector members 33 to normal position to positively withdraw the envelop from the storage compartment and present it to the printing devices, until the injector members have passed the lugs, at which time the high point of the cam 50 contacts the wiper 49 to force the latter in the opposite direction against the tension of its spring 48 and shift the restraining lugs 46 to effective position

across the channel leading from the storage compartment. The positively fed envelop is drawn over the upper ends of the lugs which then prevent additional envelops from being frictionally withdrawn from the storage compartment.

It will be readily understood that the envelops, after having been advanced by the injector mechanism, might receive the imprint from the printing devices without further adjustment, but in such event, the positions of the writing lines on the several envelops might vary, depending upon whether the machine was slowly or vigorously stroked, which uneven operation would advance some of the envelops farther than others.

I prefer to so arrange the mechanism, that the writing line will be positioned at a predetermined and constant point on each envelop, and not left to chance or accident, to which end, I provide arresting stops 51 in the channel, against which stops the bottom edges of the envelops contact, to position the envelops uniformly relatively to the printing line. The arresting stops or bars 51 are pivoted at 52 (Figs. 2 and 8) to the end frames 22, and project through slots 53 in the lower guide plate 21 (Fig. 6) and into registering slots 54 in the outer confining plate 19, as shown in Figs. 2, 4 and 7. The forward ends of the stops normally lie squarely across the channel, springs 55 (Fig. 2) secured to the opposite ends of the stops, operating to yieldingly maintain them in such effective position. Abutments 56 on the end frames 22 limit the spring-impelled throw of the arresting members 51, which lie to one side of the paths of travel of the injector members 33, and hence, do not interfere therewith. As the injector members 33 advance the envelop along the channel and in front of the platen 30, the arresting members yield upwardly against the tension of springs 55, to permit the passage of the envelop thereunder. The envelop is advanced throughout the return stroke of the main drive shaft 200 until the bottom edge of the envelop escapes past the arresting members, which thereupon snap back to active position across the feed channel, as shown in Fig. 2.

Portions of the carrier arms 32 extend into the receiving compartment, when the parts are in normal position shown in Fig. 2, and carry positioning members 57 having abrupt rear faces, pivotally mounted at 58 thereon, in front of the injector fingers 33.

The positioning members extend across the channel or passageway leading from the storage to the receiving compartment, the outer ends of the positioning members traversing slots 59 (Figs. 3 and 7) formed in the confining plate 19 near the opposite sides of the channel.

Springs 60 normally maintain the positioning members 57 in effective position across the channel, and lugs 61 limit the spring-pressed throw of the members.

5 On the forward stroke of the main drive shaft 200, when the motor spring 34 turns the shaft 23 to swing the arms 32 carrying the injector members 33 to their potentially effective position, as shown in Fig. 4, the injector fingers retire from the flap 17 to release the envelop which they have just advanced, the points only of the injector fingers traversing the channel. The abrupt faces of the positioning members 57 which 10 follow the injector fingers on this stroke, contact the envelop to feed it backwardly until its lower or bottom edge strikes the members 51, which arrest the envelop against further backward travel, so that the 15 imprint of the amount set up on the keyboard is effected at a predetermined and constant distance from the bottom edge of the envelop, whereby the writing lines on the respective envelopes occupy a uniform position.

After the arrest and alinement of the envelop, the positioning members 57 yield against the tension of their springs 60 to 20 wipe idly over the envelop to their positions shown in Fig. 4.

It will be understood that in using this attachment, the operator before setting up an amount on the keyboard, will first stroke the machine for one idle operation. The forward stroke of the main drive shaft 200, enables the shaft 23 under the influence of the motor spring 34 to retract the injector members 33 to position to engage the uppermost envelop in the storage compartment, 25 and upon the return stroke of the main drive shaft 200, the envelop is presented to the printing devices.

The operator will now set up the amount on the keyboard to be printed on the envelop and then operate the main drive shaft 200 once more, which again retracts the injector mechanism, during which operation the previously fed envelop is brought back by the positioning members 57 to contact the 30 arresting members 51. The printing devices operate near the end of the forward stroke, after which it becomes necessary to remove the printed envelop to make room for the succeeding blank envelop, which is advanced 35 to position on the return stroke of the main drive shaft.

The printed envelop might be manually withdrawn, but preferably, I provide means to automatically eject or discharge the printed envelopes and deliver them into the receiving or collection compartment, and this I accomplish by utilizing the same mechanism which positions the envelop relatively to the printing devices.

65 The envelop positioning members 57 on

the arms 32 readily lend themselves to the function of ejecting the envelops on the return stroke of the drive shaft 23, and to this end, I form hooks or lips 62 (Figs. 2 and 6) on the positioning members to constitute 70 ejecting fingers or members, it being obvious that they might be separate parts instead of integral with the positioning members.

In the normal position of the parts, at the end of the return stroke of shaft 23 (Fig. 2), 75 the ejector members lie within the receiving compartment to insure the complete withdrawal of the discharged envelopes from the channel or passageway leading from the storage compartment to the receiving compartment.

On the forward stroke of the shaft 23, the ejector members 62 follow the injector fingers 33 downwardly and rearwardly. The abrupt rear faces of the members 57 which 85 constitute the envelop positioning means, contact the forward edge of the envelop and return it until it strikes the arresting arms 51, whereupon the positioning members yield against the tension of the light springs 60 to 90 permit the members to ride over the edge of and behind the envelop, until they pass the bottom edge of the latter. The springs 60 then restore the members to normal positions with the hooks 62 facing the bottom edge of 95 the envelop, as shown in Fig. 4, and just in advance of the restraining lugs 46.

On the succeeding return stroke of shaft 23, the ejector members 62, which now lie ahead of the injector fingers 33, advance 100 against the bottom edge of the previously fed envelop and drive it along the channel or passageway between the outer confining plate 19 and the upper and lower guide plates 20 and 21, until it is discharged into 105 the receiving compartment.

It will be noted that as one envelop is being discharged, the succeeding envelop is being advanced past the printing devices by the injector members 33.

110 The envelopes are ejected with considerable force, and strike the closure 27, if the latter is in effective position, upon which the envelopes drop one after another to form a flat pile or stack on the bottom of the receiving 115 compartment.

By raising the gate 27, the envelopes, upon their ejection, will be entirely discharged from the machine, passing through the receiving compartment and out of the open 120 rear end thereof, to fall upon a table or other unconfined area to enable the paymaster to fill them in readiness for distribution or to write other data thereon, if desired, thereby effecting an economy in time and labor.

125 Attention is also directed to the fact that I have utilized rotary means for feeding and ejecting the envelopes, rather than the rectilinearly reciprocating means heretofore employed.

Such rotary arrangement enables the device to be embodied in smaller compass, or condensed and enables me to completely inclose the feed and ejecting members to protect them from injury, and yet provide for unobstructed access to the envelopes both before and after feeding them.

To enable the operator to make and preserve a list of the respective amounts printed on the separate envelopes or work pieces, simultaneously with the printing of such amounts on the envelopes, and with the same set of printing devices, I provide means, operated by the drive mechanism for the envelop injecting and ejecting means, to feed a paper strip or web 63 (Fig. 2) step by step past the idly rotating platen 30.

A roll of paper 64 (Figs. 1 and 2) is journaled on a cross rod 65 removably mounted in the side pieces 3. The forward end of the strip of paper, which may be carbonized on its inner surface, is led upwardly from the roll, behind a guide rod 66 bearing an anti-friction roll 67, thence over the convex face of the confining plate 19 in front of the platen 30 and the envelopes, as they are fed to the printing devices, and continuing upwardly, the leading edge of the web is inserted between pressure feed rolls 68 and 69 fast on shafts 70 and 71, journaled in the upper forward ends of the side plates 3, in front of a paper cutter 72. The paper lies between the printing devices and the envelopes to receive the original imprint which is transferred to the envelopes by the carbonized back of the paper web. However, the relative positions of the paper and envelopes might be changed without departing from the invention.

One of the feed roll shafts, as 71, (Figs. 1 and 4) is journaled in slots 73 in the side plates 3, and springs 74 connect the two shafts 70 and 71 to firmly grip the paper between the rolls.

The paper is fed step by step by means of a cam 75 (Fig. 1) fast on the rock shaft 23, in contact with a follower 76 on the shank 77 of a feed pawl 78 forked at 79 to embrace the drive shaft 23 for guidance, and also supported on a pin 80 passing through a slot 81 in the shank and mounted on the adjacent side plate 3. The feed pawl 78 engages a ratchet 82 fixed on one of the pressure roll shafts, as shaft 70 for instance, and a spring 83 connected to the feed pawl, normally retracts the latter.

As shaft 23 turns on its forward stroke, with the main drive shaft 200, the cam 75 rotates in the direction of the arrow (Fig. 1) and the spring 83 retracts the feed pawl 78, and causes the follower 76 to ride down to the low point of the cam. This enables the feed pawl to pass idly over at least one tooth of the ratchet 82 in readiness to turn the latter. The printing devices operate

during this forward stroke, and the paper is stationary while the imprint is being made.

On the return stroke of the shaft 23, the cam 75 forces the follower 76 and its feed pawl 78 in the opposite direction, against the tension of spring 83 to turn the ratchet 82, and pressure rolls 68, 69, to advance the paper 63 preparatory to the next printing operation.

A spring-pressed detent 84 engages the ratchet 82 to prevent reverse rotation thereof.

The paper unwinds freely from the paper supply and to prevent slack in the paper web between the paper roll on one side of the platen and the feed rolls on the opposite side of the platen, I provide a paper brake 85, (Fig. 2) comprising a plate journaled on a brace rod 4 and pressed lightly by springs 86 against the paper web 63 where it passes over the guide roll 67. Wings 87 on the braking plate embrace the paper supply roll 64, and the web, to hold the former against lateral play and to guide the web.

Obviously, the paper strip alone may be fed past the printing point to enable the operator to perform calculations in the ordinary use of the machine, when it is not desired to print envelopes, or other work pieces, by omitting to supply the storage compartment, in which case the envelop feeding mechanism will idly operate at each operation of the main drive shaft 200.

It will be noted that the injector, ejector and envelop alining devices, the means to prevent the frictional withdrawal of envelopes from the storage compartment, and also the paper web feeding mechanism are all driven from the common shaft 23.

Furthermore, the envelop feed and discharge mechanism, and the paper feed mechanism are self-contained and are readily applied to and removed from the calculating machine.

Changes may be made in the form and arrangement of the several parts, without departing from the spirit and scope of the invention.

What I claim as new, is:—

1. The combination with a calculating machine, including accumulating counters; a single set of printing devices; drive mechanism therefor; and a platen; of means operable as an incident to the registration of amounts on the counters, to automatically present envelopes singly and successively from a pack to the printing line, and to synchronously feed a work sheet step by step past the printing line, to enable amounts to be listed on the work sheet and printed on the envelopes by one type impression only.

2. The combination with a calculating machine, including accumulating counters; a single set of printing devices; and drive mechanism therefor; of means, operable as

an incident to the registration of amounts in the accumulator, to automatically present envelopes successively to the printing devices, and to feed a work sheet step by step 5 past the printing devices; and transfer means interposed between the envelop when at the printing line, and the work sheet, to enable amounts to be listed on the work sheet and printed on the envelopes by one 10 type impression only.

3. The combination with a calculating machine, including accumulating counters; a single set of printing devices; and drive mechanism therefor; of means, operable as 15 an incident to the registration of amounts in the accumulator, to automatically present envelopes successively to the printing devices, and to simultaneously feed a work sheet step by step past the printing devices; 20 and transfer means interposed between the envelop when at the printing line, and the work sheet to enable amounts to be listed on the work sheet and printed on the envelopes by one type impression only.

25 4. The combination with a calculating machine, including accumulating counters; a single set of printing devices; and drive mechanism therefor; of means operable incidentally to the registration of amounts on 30 the counters, to automatically present envelopes successively to the printing devices, and to feed a work sheet between the envelopes and printing devices, and transfer means between the work sheet and envelopes.

35 5. The combination in a calculating machine, including an accumulator; a single set of printing devices; and drive mechanism therefor; of a self-contained envelop and work sheet feeding mechanism attachable to and detachable from the calculating machine as a unit; and operated from the machine to automatically present envelopes successively to the printing line, and to feed 40 a work sheet step by step past the printing line.

45 6. The combination in a calculating machine, including an accumulator; a single set of printing devices; and drive mechanism therefor; of a self-contained combined envelop and work sheet-feeding attachment 50 removably connected to the machine, and including a platen; and means operable from the machine incidentally to the registration of amounts on the accumulator, to automatically 55 present envelopes successively from a pack to the printing line, and to feed a work sheet step by step past the printing line.

7. The combination in a calculating machine, with accumulating counters; a series 60 of printing devices; and drive mechanism for the counters and printing devices; of a storage compartment; a unitary injector and ejector operated from the drive mechanism, adapted to withdraw the envelopes singly 65 from the supply in the storage compartment

and positively present them to the printing devices, and to positively engage and discharge the preceding envelop as the succeeding envelop is advanced; paper web supporting mechanism; and means operable 70 with the advance of the envelopes to feed the paper web step by step.

8. The combination in a calculating machine, with accumulating counters; a series of printing devices; and a total key and 75 connections for controlling the counters; drive mechanism for the counters and printing devices; of a storage compartment; an injector and ejector operated from the drive mechanism, adapted to withdraw the envelopes singly from the supply in the storage compartment to present them to the printing devices, and to positively engage and discharge the preceding envelop as the succeeding envelop is advanced; paper web supporting mechanism; and means operable 80 with the discharge of the envelopes to feed the paper web step by step.

9. The combination in a calculating machine, having accumulating counters; a series of printing devices; and drive mechanism; of a detachable envelop and paper feeding mechanism, including a storage for envelopes, and a paper supply; means to advance envelopes singly from the storage to 95 the printing devices, and for ejecting a previously fed envelop as the succeeding envelop is advanced; and means to advance the paper step by step to the printing devices.

100 10. The combination in a calculating machine, having accumulating counters; a series of printing devices; and drive mechanism; of a support for envelopes and paper, detachably secured to the machine; and 105 combined means to advance the envelopes singly from the support to the printing devices; and for ejecting a previously fed envelop as the succeeding envelop advances; and for feeding the paper step by step in 110 front of the printing devices simultaneously with the advance of the envelop.

11. The combination with a calculating machine having accumulating and printing mechanism; of a combined envelop and 115 work sheet feeding mechanism associated therewith and including a storage compartment for a pack of envelopes; means to present the envelopes singly to the printing mechanism; means to positively engage and 120 eject the envelopes; and means to simultaneously advance the work sheet step by step past the printing mechanism.

12. The combination with a calculating machine, including accumulating counters; 125 a single set of printing devices; and drive mechanism for the counters and printing devices; of a container for separate work pieces arranged in a pile; a work sheet adapted to travel past the printing devices; 130

and mechanically-operable means to withdraw work pieces singly and successively from the container and advance them to the printing line, and to synchronously feed the work sheet step by step past the printing line, to enable amounts to be listed on the work sheet and printed on the envelope by one type impression only.

13. The combination with a calculating machine having accumulating and printing devices; of a combined envelop and paper feeding mechanism, including a storage compartment for the envelopes; a paper supply; a platen located opposite the printing devices; injecting mechanism to withdraw the envelopes singly from the compartment and advance them between the platen and the printing devices; ejecting mechanism to discharge the printed envelopes; paper feed mechanism located on the opposite side of the platen from the paper supply to advance the paper step by step past the platen; and means operated from the calculating machine to drive the injecting and ejecting mechanisms, and the paper feed mechanism.

14. The combination with a calculating machine having accumulating and printing devices; of a combined envelop and paper feeding mechanism, including a storage compartment for the envelopes; a paper supply; pressure rolls between which the paper is inserted; a platen located opposite the printing devices and between the paper supply and pressure rolls; a rock shaft driven from the calculating machine; a cam on the shaft; a ratchet on one of the pressure rolls; a drive member for the ratchet, operated by the cam; means on the rock shaft to withdraw the envelopes singly from the compartment and advance them between the printing devices and platen; and means to eject the envelopes.

15. The combination with accumulating and printing mechanisms; of a storage compartment for envelopes; injector members to withdraw the envelopes successively from the storage compartment; means to positively locate the lower edge of each envelop a predetermined distance from the printing line to insure uniformity of the impressions; ejector members to discharge the previously injected envelopes; and a work sheet feeding mechanism associated with the envelop feeding mechanism.

16. The combination in a calculating machine, with accumulating counters; a platen; printing types and drive mechanism therefor; of a unitary injector and ejector mechanism also operated from the drive mechanism, the injector adapted to withdraw single work pieces from a supply and present them to the printing types at one operation, and the ejector located ahead of and traveling with the injector, to positively engage and discharge the preceding work

piece from in front of the printing types as the succeeding work piece is advanced to the printing types by the injector.

17. The combination with a calculating machine having accumulating and printing mechanism; of a combined envelop and work sheet feeding means detachably connected with the machine, and including a storage compartment for the envelopes; a master shaft; means operated by the master shaft to present the envelopes singly to the printing mechanism and to eject the envelopes; and means likewise operated by the master shaft to advance the work sheet step by step past the printing mechanism, as an incident to the operation of the envelop presenting and ejecting means.

18. The combination with a calculating machine, having printing devices; and positioning and drive means therefor; of a combined work piece and work sheet feeding means detachably connected to the machine; injector means operated by the drive means to present the work pieces singly to the printing devices; ejector means also operated by the drive means simultaneously with the injector means, to discharge the work pieces; and feed mechanism operated by the drive means, to advance the work sheet step by step past the printing devices as an incident to the operation of the injector and ejector means.

19. The combination with a printing mechanism, including types; of a single means having a back and forth travel, to feed work pieces from a supply to the printing point opposite the types; and combined positioning and ejecting means, operable upon the withdrawal of the feed means, to shift the advanced work pieces relatively to the printing point, to cause the imprint to be uniformly located on each work piece, said combined means operable, upon the advance of the feed means, to eject the previously fed work pieces from in front of the types.

20. The combination with a printing mechanism, including types; of a single means having a back and forth travel, to feed work pieces from a supply to the printing point opposite the types; means operable upon the withdrawal of the feed means, to shift the advanced work pieces relatively to the printing point, to cause the imprint to be uniformly located on each work piece; and ejecting means traveling ahead of the feed means to positively engage and discharge the previously fed work piece.

21. The combination with accumulating and printing mechanisms; of a feeding and discharging means for work pieces, operable as an incident to the operation of the accumulating and printing mechanisms, and including an injector to advance the work pieces successively to the printing mecha-

- 5 nism; means to positively locate the work pieces in such position relatively to the printing mechanism, that the printing will occur at a uniform point on each work piece; an ejector to discharge the work pieces; and a work sheet feeding mechanism associated with the work piece feeding and ejecting means, and operable coincidently therewith.
- 10 22. The combination with a printing mechanism, including types; of a single means having a back and forth travel, to feed work pieces from a supply to the printing point opposite the types; alining stops in the path traversed by the work pieces; and means operable upon the withdrawal of the feed means, to shift the advanced work pieces into contact with the alining stops, to cause the imprint to be uniformly 15 located on each work piece, and to eject the advanced work pieces.
- 20 23. The combination with a printing mechanism including types; a storage compartment for work pieces arranged in a pack therein; and a platen located opposite the types; of an oscillatory work piece feeding device adapted, on its forward stroke, to travel from the storage compartment to a point past the printing line on the platen, 25 to positively advance the work pieces individually from the storage compartment to printing position, at a single operation; alining stops past which the work pieces are advanced by the feeding device; and means 30 on the feeding device to contact the advanced work piece on the return stroke of the device, and retire the work piece until it abuts the alining stops.
- 35 24. The combination with a calculating machine, including accumulating counters; a series of printing devices; and drive mechanism therefor; of injector means, operable incidentally to the operation of registering amounts on the counters, to present envelopes from a pack successively to the printing devices; means to positively engage and discharge the envelopes from in front of the printing devices; a container into which the envelopes are discharged; and 40 shiftable means to normally retain the discharged envelopes in the container.
- 45 25. The combination with printing devices; and a platen; of a carrier shiftable relatively to the platen; injecting and ejecting means mounted on the carrier, the carrier having a forward and a return stroke, the injecting means adapted to withdraw the work pieces individually from a pack and advance them to position in front of 50 the platen, during a single forward stroke; and the ejecting means adapted to discharge a previously advanced work piece from in front of the platen ahead of the succeeding work piece during the same stroke.
- 55 26. The combination with a calculating machine having printing devices; of an envelop feed mechanism, including a storage compartment for the envelopes; a platen located opposite the printing devices; shiftable carriers; means to drive the carriers back and forth; means mounted on the carriers to engage and withdraw the envelopes singly from the compartment and advance them between the platen and the printing devices; and ejecting members also mounted on the carriers to discharge the previously fed envelop from between the platen and the printing devices as the succeeding envelop is advanced.
- 60 27. The combination with a calculating machine having printing devices; of an envelop feeding mechanism, including a storage compartment for the envelopes with a passageway leading therefrom past the printing devices; and interrupted at a point opposite the printing devices; a platen located opposite the printing devices and extending into the passageway at its point of interruption; swinging injector fingers located on opposite sides of the passageway to withdraw the envelopes singly from the compartment and advance them between the printing devices and platen; and yielding ejector members adapted to wipe over the advanced envelopes in one direction and to discharge the envelopes when traveling in the opposite direction, ahead of the succeeding envelop as it is advanced by the injector fingers.
- 65 28. The combination with a calculating machine, including accumulating mechanism; types; type-actuating means; and a platen; of work piece feeding and delivering means operable independently of the platen, and including an injector, having a forward and a backward stroke, the injector adapted, upon its forward stroke, to first abstract the work pieces individually from a pack and then introduce them between the platen and the types; alining stops past which the work piece is fed by the injector; and an ejector traveling ahead of the injector and relatively to the platen, to discharge a previously fed work piece from in front of the types as the succeeding work piece advances to the types, during its forward stroke, the injector adapted to release the work piece on its backward stroke, and the ejector adapted to first back the work piece against the alining stops during the same stroke, and then assume a position to discharge the work piece from between the types and platen, on the next forward stroke.
- 70 29. The combination with a calculating machine having printing devices; of an envelop feeding mechanism, including a platen located opposite the printing devices; a storage compartment for a pack of envelopes; a
- 75 80 85 90 95 100 105 110 115 120 125 130

- follower self-adjustable to the plane of the stored envelops; a stop plate against which the envelops are pressed by the follower; alining guides projecting from the stop plate to register the envelops at the discharge end of the pack; and means to withdraw the envelops singly from the storage compartment and advance them between the printing devices and the platen.
30. The combination with a calculating machine having printing devices; of an envelop feeding mechanism, including a platen located opposite the printing devices; a storage compartment for a pack of envelops, having slots in its side walls; pivoted spring-pressed arms arranged externally of the compartment; a rod passing through the slots to connect the arms; a follower within the compartment pivoted on the rod; a spring to press the follower against the envelops; a stop plate against which the envelops are pressed; and means to withdraw the envelops singly from the compartment and advance them between the printing devices and the platen.
31. The combination with a calculating machine having accumulating, and printing devices; of an envelop feeding mechanism, including a storage compartment for the unprinted envelops; a receiving container for the printed envelops, connected by a passage with the storage compartment; a platen interposed in the passage; and means to withdraw the envelops singly and successively from the storage compartment, advance them through the passage past the platen and printing devices, and eject them into the receiving container.
32. The combination with a calculating machine having printing devices; of a work piece feeding mechanism, including a storage compartment for the work pieces; opposed guide members leading from the compartment, between which is formed a passageway in communication with the compartment; a platen located opposite the printing devices, with its periphery extending into the passageway; and a single injector means adapted to traverse the passageway, to engage and withdraw the work pieces singly from the compartment and advance them along the passageway to a point between the platen and the printing devices.
33. The combination with a calculating machine having printing devices; of an envelop feed mechanism, including a casing detachably secured to the machine, and having a storage compartment for the envelops, and a passageway in communication with the compartment; a platen mounted in the casing opposite the printing devices and extending into the passageway; means to engage and withdraw the envelops singly from the compartment and advance them along the passageway, and between the platen and the printing devices; said casing also having a compartment for the reception of the printed envelops; and means to eject the printed envelops thereinto.
34. The combination in a calculating machine, with accumulating, and printing devices; and drive mechanism therefor; of means to present envelops singly from a pack to the printing devices, including a storage chamber wherein the envelops are arranged with their flaps headed toward the printing devices; a plate partially closing the storage chamber, and having a deflected portion to contact the envelops at a point behind the flaps of the envelops; means to press the envelops against the deflected portion to cause the flap of the foremost envelop to lift above the plate; and injector members insertible between the flap of the foremost envelop and its body portion, to advance the envelop to the printing devices.
35. The combination with a calculating machine, including accumulating counters; a series of printing devices; and drive mechanism therefor; of a combined injector and ejector mechanism operable incidentally to the registration of amounts on the counters, to advance envelops successively from a pack to the printing devices at a single stroke, and to discharge a previously fed envelop ahead of the advancing envelop; and mechanically-operated means positively shifted into and out of the path of the envelop to prevent the withdrawal of more than one envelop from the pack at a time.
36. The combination with accumulating and printing mechanisms; of a storage compartment for envelops; injector members to withdraw the envelops successively from the storage compartment; means to locate the envelops in front of the printing devices; ejector members to discharge the previously injected envelops; and means positively operated synchronously with the injector members to enter and withdraw from the path of the envelop to prevent the withdrawal of a plurality of envelops from the storage compartment at one time.
37. The combination with a calculating machine, including accumulating counters; printing devices; and drive mechanism therefor; of injector mechanism adapted to withdraw envelops from a pack and present them to the printing devices; restraining means normally lying across the path of the envelops to prevent the frictional withdrawal of envelops from the pack; and mechanically operated means to positively shift the restraining means to, and retain it temporarily in, its inactive position, to permit the passage of the envelop advanced by the injector mechanism.
38. The combination with a calculating machine, including accumulating counters; printing devices; and drive mechanism

therefor; of injector mechanism adapted to withdraw envelops from a pack and present them to the printing devices; and restraining means mechanically shiftable into and 5 out of the path of the injector mechanism to prevent the accidental withdrawal of envelops from the pack, and to permit the passage of the injector mechanism.

39. The combination with a calculating 10 machine, including accumulating counters; printing devices; and drive mechanism therefor; of injector mechanism adapted to withdraw envelops from a pack; shiftable restraining means normally lying in the 15 path of the injector mechanism, to prevent the accidental withdrawal of envelops; and timing mechanism to shift the restraining means in synchronism with the injector mechanism and relatively thereto to enable 20 the latter to pass the restraining means.

40. The combination with a calculating 25 machine, including accumulating counters; printing devices; and drive mechanism therefor; of injector mechanism adapted to withdraw envelops from a pack; shiftable restraining means normally lying in the 30 path of the injector mechanism, to prevent the accidental withdrawal of envelops; and a cam to shift the restraining means in synchronism with the injector mechanism and relatively thereto to enable the latter to pass the restraining means.

41. The combination with a calculating 35 machine, including accumulating counters; printing devices; and drive mechanism therefor; injector members adapted to withdraw envelops from a pack; shiftable restraining means normally lying in the path 40 of the injector members, to prevent the accidental withdrawal of envelops; a rock shaft to operate the injector members; and timing mechanism controlled by the rock 45 shaft, to shift the restraining means in synchronism with the injector members and relatively thereto, to enable the latter to pass the restraining means.

42. The combination with a calculating 50 machine, including accumulating counters, a series of printing devices; and drive mechanism therefor; of means operable incidentally to the registration of amounts on the counters, to advance the writing lines on successive envelops past the printing line, at a single stroke; arresting means; and positioning members adapted to aline the bottom edges of the envelops against the arresting means on the opposite stroke of the envelop-advancing means, to locate the writing lines on the envelops uniformly at the 60 printing line.

43. The combination with a calculating 65 machine, including accumulating counters; a series of printing devices; and drive mechanism therefor; of means to successively present envelops to the printing devices, as an

incident to the operation of accumulation on the counters; positioning members operable to engage and adjust the envelops subsequently to their presentation to the printing devices; and envelop-arresting means 70 against which the edges of the envelops are alined by the positioning members to uniformly locate the writing line at a predetermined distance from such bottom edge.

44. The combination with a calculating 75 machine, including accumulating counters; a series of printing devices; and drive mechanism therefor; of means adapted to feed work pieces one by one from a pack to the printing devices; and means to adjust 80 the work pieces, subsequently to the withdrawal of the feed means, to locate the writing line at a predetermined point on each work piece.

45. The combination with printing 85 devices; of a means to withdraw work pieces one by one from a pack and advance them to a point opposite the printing devices; alining stops; and means to engage the work pieces subsequently to their withdrawal from the pack, and adjust them backwardly against the alining stops and relatively to the printing devices, to locate the writing line at a predetermined point on each work piece. 95

46. The combination with a calculating 100 machine, including accumulating counters; a series of printing devices; and drive mechanism therefor; of a combined injector and ejector mechanism operable incidentally to the registration of amounts on the counters, to advance envelops successively from a pack to the printing devices at a single stroke, and to discharge a previously fed envelop ahead of the advancing envelop; 105 arresting means with which the envelops contact to locate the writing line on the respective envelops, and means operable upon the retraction of the injector mechanism from the envelop, to aline each envelop 110 against the arresting means.

47. The combination with accumulating 115 and printing mechanisms; of a storage compartment for envelops; injector members to withdraw the envelops successively from the storage compartment; and present them in front of the printing devices; arresting means to locate the writing line at a predetermined point from the bottom of the envelop; means to adjust the envelops against 120 the arresting means subsequently to their presentation in front of the printing devices and ejector members to discharge the envelop from in front of the printing devices. 125

48. The combination with a calculating machine having a printing mechanism; of a work piece feeding device, including a platen located opposite the printing mechanism; a storage compartment for the work 130

pieces; injector; means having a forward and a return stroke, and adapted, on its forward stroke, to withdraw the work pieces singly from the compartment and introduce them between the platen and the printing mechanism; stop devices and means operable as an incident to the return of the injector means, to align the work pieces against the stop devices to locate the printing line; at a predetermined point on the respective work pieces.

49. The combination with printing devices; and drive means therefor; of a work piece feeding mechanism operated by the drive means, including injector members to withdraw the work pieces from a pack and present them to the printing devices; arresting means past which the work pieces are fed by the injector members; and means to back up the work pieces against the arresting means on the retraction of the injector members, to locate the writing line on the work pieces at a predetermined point on the respective work pieces.

50. The combination with printing devices; and drive means therefor; of a work piece feeding and ejecting mechanism operated by the drive means, including injector members to withdraw the work pieces from a pack and present them to the printing devices; arresting means past which the work pieces are fed by the injector members; and means to back up the work pieces against the arresting means on the retraction of the injector members, to locate the writing line on the work pieces at a predetermined point on the respective work pieces, and to eject the work pieces from in front of the printing devices subsequently to the printing operation.

51. The combination with a calculating machine having a printing mechanism; of an envelop feeding device, including a platen located opposite the printing mechanism; a storage compartment for the envelops; means to withdraw the envelops singly from the compartment and advance them past the printing line on the platen, and to return them to the printing line; and arresting means against which the envelops contact on their return to locate the printing line at a predetermined point on each envelop.

52. The combination with a calculating machine having printing devices; of an envelop feeding mechanism, including a storage compartment for the envelops; a platen located opposite the printing devices; an injector mechanism to withdraw envelops singly from the compartment and advance them between the printing devices and platen; means to return the envelops from their advanced positions; and yielding stops to enable the envelops to advance and to arrest the envelops on their retirement, to lo-

cate the printing at a predetermined writing line on the envelop.

53. The combination with a calculating machine having printing devices; of an envelop feeding mechanism, including a storage compartment for the envelops; a platen located opposite the printing devices; an injector mechanism to withdraw envelops singly from the compartment and advance them between the printing devices and platen; and flexible ejector members adapted to contact with the advanced envelops to retire them; yielding stops to arrest the envelops on such retirement, to enable the ejector members to ride idly over the envelop in one direction, to a point behind the stops, to discharge the envelop, when traveling in the opposite direction, ahead of the succeeding envelop as the latter is advanced by the injector mechanism.

54. The combination with a calculating machine having printing devices; of an envelop feeding mechanism, including a casing having a storage compartment for the envelops; a platen located opposite the printing devices; a rock shaft journaled in the casing; means operated from the calculating machine to drive the shaft; arms on the shaft; injector fingers on the arms adapted to engage beneath the flaps of the individual envelops to positively withdraw them singly from the compartment and advance them between the printing devices and the platen; yielding stops past which the injector fingers advance the envelops; and combined positioning and ejector fingers pivoted to the arms in front of the injector fingers to retire the advanced envelop against the stops and then ride idly over the envelop, when traveling in one direction, and to engage and discharge the advanced envelop on the return stroke, ahead of the succeeding envelop advanced by the injector fingers on such stroke.

55. The combination with a calculating machine, having printing devices; of an envelop feed and discharge mechanism, including means to advance the envelops singly and successively to the printing devices; and means traveling with the feed means and adapted to wipe over the advanced envelops, and take up a position to contact the rear edges of the envelops to positively eject them in front of the printing devices, as the feed means retires to engage another envelop preparatory to advancing the latter.

56. The combination with a calculating machine, having printing devices; of an envelop feed and discharge mechanism including means to advance the envelops singly and successively to the printing devices; and means operable substantially synchronously with the envelop advancing means as the latter returns for the next envelop, to clear the bottom edge of the previously fed envelop.

envelop, and to eject the latter as the feed means advances the succeeding envelop.

57. The combination with a calculating machine, having printing devices; of an envelop feed and discharge mechanism, including means to advance the envelopes singly and successively to the printing devices; and means to wipe past the advanced envelop to position to contact the bottom edge of the 10 envelop and eject the latter as the envelop advancing means feeds the succeeding envelop.

58. The combination with a calculating machine, having printing devices; of an envelop feed and discharge mechanism, including means to advance the envelopes singly and successively to the printing devices; and flexible ejector fingers adapted to pass in one direction over the advanced envelop until they clear the bottom edge thereof, to contact such edge and eject the envelop, on the return stroke.

59. The combination with a machine having printing devices; of a storage compartment for separate work pieces, in communication with a passage leading past the printing devices; means to advance envelopes singly and successively from the storage compartment through the passage, to the printing devices; and flexible ejecting fingers adapted to ride over the advanced envelop until past the bottom edge thereof, to contact such bottom edge and eject the envelop through the passage.

35 60. The combination with a machine having printing devices; of means to feed work pieces separately thereto; alining members past which the work pieces are fed; and positioning members to return the work pieces 40 against the alining members in position to take the imprint.

61. The combination with a machine having printing devices; of means to feed work pieces separately thereto; alining members 45 past which the work pieces are fed; and combined positioning and ejecting members to first return the work pieces against the alining members in position to take the imprint, and to discharge the work pieces from 50 in front of the printing devices.

62. The combination with a machine having printing devices; of means to feed work pieces separately thereto; alining members past which the work pieces are fed; combined positioning and ejecting members to 55 first return the work pieces against the alining members in position to take the imprint, and to discharge the work pieces from in front of the printing devices as the succeeding work piece is advanced; and a drive means common to the envelop feeding, positioning and ejecting members.

63. The combination with a machine having printing devices; of a storage compartment 65 for separate work pieces; injector

members to withdraw the work pieces singly and successively from the compartment and present them to the printing devices; alining members beyond which the work pieces are advanced; shiftable restraining means normally in the path of the injector members, to prevent the accidental withdrawal of the work pieces; combined positioning and ejector members adapted to return the advanced work pieces against 75 the alining members to uniformly locate the writing line on the respective work pieces, and to eject the work pieces after the printing operation; and drive mechanism common to the injector members, the restraining means, the combined positioning and ejector members.

64. The combination with a calculating machine, including printing devices, and operating mechanism therefor; of means to automatically advance work pieces to and to discharge them from in front of the printing devices, including swinging feeding members, to present the work pieces successively to the printing devices; and swinging ejector 85 members to discharge a previously fed work piece from in front of the printing devices, just ahead of the succeeding work piece as it is advanced to the printing devices.

65. The combination with a calculating machine, including printing devices, and operating mechanism therefor; of means to automatically present work pieces to the printing devices, including a rotatable carrier; injector and ejector members mounted thereon; and alining means with which the envelopes are caused to contact by the ejector members.

66. The combination with a calculating machine, including printing devices; and operating mechanism therefor; of a storage for work pieces located apart from the printing devices; means to withdraw the work pieces from the storage and present 100 them to the printing devices, including injector members driven by the operating mechanism; guide means leading from the storage toward the printing devices and forming a passageway along which the work 105 pieces are advanced by the injector members; and a platen located opposite the printing devices, the passageway extending tangentially of the periphery of the platen.

67. The combination with a calculating machine, having printing means; and operating mechanism therefor; of a work piece feed and discharge device, including storage and collection compartments for the work pieces; injector members to withdraw 120 the work pieces from the storage compartment and present them to the printing means; guide means extending between and connecting the storage and collection departments, and forming a passageway along 125 130

which the work pieces travel, one wall of the guide means being apertured at a point intermediate the storage and collection compartments opposite the printing means; and 5 a platen, the periphery of which interrupts the opposite wall of the passageway.

68. The combination with a calculating machine, including printing devices; and operating mechanism therefor; of a storage 10 compartment for work pieces, located apart from the printing devices; oscillatory injector members driven by the operating mechanism, to withdraw the work pieces from the storage compartment and present 15 them to the printing devices; guide means curved to conform to the path of travel of the injector members, and leading from the storage compartment toward the printing devices, to form a passageway along which 20 the work pieces travel; a platen located opposite the printing devices and projecting into the passageway; a collection compartment with which the passageway connects; and 25 ejector members to cause the work pieces to traverse the remainder of the passageway and discharge them into the collection compartment subsequent to the operation of the printing means.

69. The combination with a calculating 30 machine, having printing devices; and operating mechanism therefor; of means to automatically present work pieces to the printing devices, including oscillatory injector members adapted to remove the work 35 pieces singly from a pile and advance them to the printing devices; oscillatory ejector members adapted to discharge the work pieces subsequently to the operation of printing thereon; and means to wholly inclose 40 the injector and ejector mechanism to protect them against injury.

70. The combination with a calculating 45 machine, having printing devices; and operating mechanism therefor; of means to automatically present work pieces to the printing devices, including a casing having storage and receiving compartments for the

work pieces accessible at all times, and a guide means to connect the compartments; oscillatory injector members to remove the 50 work pieces from the storage compartment and feed them to the printing devices; and oscillatory ejector members to discharge the work pieces from in front of the printing devices, into the receiving compartment. 55

71. The combination with a calculating machine, having printing devices; and operating mechanism therefor; of means to automatically present work pieces to the printing devices; means to forcibly and positively eject the work pieces from in front of the printing devices; a receiving compartment into which the work pieces are ejected, and having an opening in line with the path of flight of the ejected work pieces 60 to enable them to pass through and fall beyond the compartment; and a displaceable closure for the opening to cause the work pieces to stack in the compartment when desired. 70

72. The combination with a calculating machine, including accumulating mechanism; types; type-actuating means; and a platen; of means to introduce work pieces between the types and platen; alining stops 75 past which the work pieces are fed in their advance to printing position; and a shiftable ejecting means adapted on one stroke to contact the leading edges of the work pieces to back them up against the alining 80 stops, and then assume a position whereby to eject the work pieces on its opposite stroke.

73. The combination with printing devices and a platen; of means to feed work 85 pieces from a pack, and introduce them between the printing devices and platen; alining stops past which the work pieces travel in their advance to the printing devices and platen; and means to contact the work 90 pieces and return them against the alining stops.

AMBROSIUS BRIECHLE.
